FLAT SHEET DELIVERY FOR WEB PRINT-
ING ROTARY PRESSESHoward M. Barber, Pawcatuck, Conn., assignor
to C. B. Cottrell & Sons Company, Westerly,
R. I., a corporation of Delaware

Application June 25, 1936, Serial No. 87,155

8 Claims. (Cl. 271—76)

In high speed web printing rotary presses having flat sheet deliveries it is desirable that the speed of the sheets be materially reduced on their way to the delivery piles. I have found that 5 by providing stationary supports over which the sheets are drawn as they are forwarded from the sheet collecting rotary carriers to the oppositely disposed sheet delivery endless carriers, the sheet transfer rotary carriers may be driven at 10 the same high surface speed as the sheet collecting rotary carriers and that the endless sheet delivery carriers may be driven at a slower surface speed, it being understood that the higher surface speed of the sheet transfer rotary carriers will not affect the sheets after their leading 15 ends have been taken by the sheet delivery endless carrier grippers because the sheets are being drawn over the said stationary supports by the slower moving sheet delivery endless carrier grippers.

A practical embodiment of my invention is represented in the accompanying drawing, in which the figure represents a diagrammatic side elevation of a double flat sheet delivery.

25 The traveling web 1 is led through the coacting rotary cutters 2, 3, the guides 4, 5, the rolls 6, 7, and the guides 8, 9 to a point between the sheet collecting rotary carriers 10, 11. Single sets of grippers 12 and 13 on the sheet collecting 30 rotary carriers 10 and 11 respectively, collect alternate sheets cut from the traveling web. In the present instance the sheets are collected in groups of two. These sheet collecting rotary carriers are driven at a surface speed equal to 35 the speed of travel of the web, by any well known or approved means (not shown herein).

The sheet transfer rotary carriers 14, 15 are driven at the surface speed of the sheet collecting rotary carriers 10, 11, as for instance through 40 the pairs of gears 16, 17 and 18, 19 respectively. These sheet transfer rotary carriers are shown herein as having twice the circumference of the sheet collecting rotary carriers and as being provided with single sets of grippers 20, 21, arranged 45 to coact with the single sets of grippers 12, 13 on the sheet collecting rotary carriers 10, 11, to take a collected group of sheets from the said sheet collecting rotary carriers.

Oppositely disposed sheet delivery endless carriers 22, 23 of the well known sprocket chain type pass around inner and outer sprocket wheels 24, 25 and 26, 27 respectively, which endless carriers are driven at a surface speed less than that of the collecting and transfer rotary carriers, as 55 for instance through the gears 28, 29 and 30, 31

respectively. These sheet delivery endless carriers are provided with spaced sets of grippers 32, 33, arranged to take the leading ends of the collected groups of sheets from the sheet transfer rotary carrier grippers 20 and 21 respectively. 5

Because the surface speed of the sheet delivery endless carriers is less than the surface speed of the sheet collecting and transfer carriers, I provide curved stationary supports 34, 35 over which the groups of sheets travel as they are forwarded 10 by the sheet transfer rotary carrier grippers 20 and 21 from the sheet collecting rotary carrier grippers 12 and 13 to the sheet delivery endless carrier grippers 32 and 33. This permits the sheet transfer rotary carriers 14, 15 to travel at 15 the same surface speed as the sheet collecting rotary carriers 10, 11 without disturbing the slower travel of the groups of sheets after their leading ends have been taken by the sets of grippers 32, 33 on the slower moving sheet delivery endless carriers 22 and 23.

The means which I have shown for taking the sheets from the sheet delivery endless carrier and depositing them flat onto the piles 36, 37 are shown herein as sheet tail end engaging mechanisms 38 and 39 respectively, of well known or approved form, such for instance as the mechanism disclosed in my copending application filed May 20, 1936, Serial No. 80,667, each of which mechanisms comprises, generally, coacting rotary 30 and oscillating nippers 40, 41 driven from the sheet delivery endless carrier and operable to depress the tail ends of the sheets, retard, and stop the sheets and deposit them onto their delivery pile. 35

From the above description it will be seen that by providing the curved stationary supports which partially surround the sheet transfer carriers the collected groups of sheets are drawn along the supports first at the speed of the web, 40 by the transfer carrier grippers and then at a lesser speed by the delivery carrier grippers, thereby allowing the transfer carriers to travel at the surface speed of the sheet collecting carriers and yet permit the groups of sheets to be 45 slowed down as soon as their leading ends have been taken by their respective delivery carrier grippers.

It will also be seen that the sheet tail end nippers serve to still further retard and to stop 50 the travel of the sheets before they are deposited upon their respective piles.

It is evident that various changes may be resorted to in the construction, form and arrangement of the several parts without departing 55

from the spirit and scope of my invention, and hence I do not intend to be limited to the particular embodiment herein shown and described, but—

5. What I claim is:

1. Means for cutting sheets from a traveling web, and a double flat sheet delivery therefor comprising two rotary carriers, each arranged to collect a group of sheets, two oppositely disposed sheet delivery carriers, two rotary carriers for transferring the collected groups of sheets from their respective sheet collecting carriers to their respective sheet delivery carriers, and curved stationary sheet supports along the convex sides of which the sheets are drawn as they are forwarded by the sheet transfer and delivery carriers, said sheet supports partially surrounding the upper sides of their respective transfer carriers and located between them and their sheet collecting and delivery carriers.

2. Means for cutting sheets from a traveling web, and a double flat sheet delivery therefor comprising two rotary carriers, each arranged to collect a group of sheets, two oppositely disposed sheet delivery endless carriers, two rotary carriers for transferring the collected groups of sheets from their respective sheet collecting carriers to their respective sheet delivery endless carriers, and curved stationary sheet supports along the convex sides of which the sheets are drawn as they are forwarded by the sheet transfer and delivery carriers, said sheet supports partially surrounding the upper sides of their respective transfer carriers and located between them and their sheet collecting and delivery carriers.

3. Means for cutting sheets from a traveling web, and a double flat sheet delivery therefor comprising two rotary carriers, each arranged to collect a group of sheets, two oppositely disposed sheet delivery carriers, two rotary carriers for transferring the collected groups of sheets from their respective sheet collecting carriers to their respective sheet delivery carriers, and curved stationary sheet supports along the convex sides of which the sheets are drawn as they are forwarded by the sheet transfer and delivery carriers, said sheet supports partially surrounding the upper sides of their respective transfer carriers and located between them and their sheet collecting and delivery carriers, means for driving the sheet collecting and transfer carriers at the surface speed of the web and the sheet delivery carriers at a lesser surface speed.

55. 4. Means for cutting sheets from a traveling web, and a double flat sheet delivery therefor comprising two rotary carriers, each arranged to collect a group of sheets, two oppositely disposed sheet delivery endless carriers, two rotary carriers for transferring the collected groups of sheets from their respective sheet collecting carriers to their respective sheet delivery endless carriers, and curved stationary sheet supports along the convex sides of which the sheets are drawn as they are forwarded by the sheet transfer and delivery carriers, said sheet supports partially surrounding the upper sides of their respective transfer carriers and located between them and their sheet collecting and delivery carriers, means for driving the sheet collecting and transfer carriers at the surface speed of the web and the sheet delivery carriers at a lesser surface speed.

5. Means for cutting sheets from a traveling web, and a double flat sheet delivery therefor

comprising two rotary carriers, each having a single set of grippers arranged to collect a group of sheets, two sheet delivery carriers having spaced sets of grippers, two rotary carriers having single sets of grippers for transferring the collected groups of sheets from their respective sheet collecting carrier grippers to their respective sheet delivery carrier grippers, and curved stationary sheet supports along the convex sides of which the sheets are drawn as they are forwarded by the sheet transfer and delivery carriers, said sheet supports partially surrounding the upper sides of their respective transfer cylinders and located between them and their sheet collecting and delivery carriers.

6. Means for cutting sheets from a traveling web, and a double flat sheet delivery therefor comprising two rotary carriers, each having a single set of grippers arranged to collect a group of sheets, two sheet delivery endless carriers having spaced sets of grippers, two rotary carriers having single sets of grippers for transferring the collected groups of sheets from their respective sheet collecting carrier grippers to their respective sheet delivery endless carrier grippers, and curved stationary sheet supports along the convex sides of which the sheets are drawn as they are forwarded by the sheet transfer and delivery carriers, said sheet supports partially surrounding the upper sides of their respective transfer cylinders and located between them and their sheet collecting and delivery carriers.

7. Means for cutting sheets from a traveling web, and a double flat sheet delivery therefor comprising two rotary carriers, each having a single set of grippers arranged to collect a group of sheets, two sheet delivery carriers having spaced sets of grippers, two rotary carriers having single sets of grippers for transferring the collected groups of sheets from their respective sheet collecting carrier grippers to their respective sheet delivery carrier grippers, and curved stationary sheet supports along the convex sides of which the sheets are drawn as they are forwarded by the sheet transfer and delivery carriers, said sheet supports partially surrounding the upper sides of their respective transfer cylinders and located between them and their sheet collecting and delivery carriers, means for driving the sheet collecting and transfer carrier grippers at the surface speed of the web and the sheet delivery carrier grippers at a lesser surface speed.

8. Means for cutting sheets from a traveling web, and a double flat sheet delivery therefor comprising two rotary carriers, each having a single set of grippers arranged to collect a group of sheets, two sheet delivery endless carriers having spaced sets of grippers, two rotary carriers having single sets of grippers for transferring the collected groups of sheets from their respective sheet collecting carrier grippers to their respective sheet delivery endless carrier grippers, and curved stationary sheet supports along the convex sides of which the sheets are drawn as they are forwarded by the sheet transfer and delivery carriers, said sheet supports partially surrounding the upper sides of their respective transfer cylinders and located between them and their sheet collecting and delivery carriers, means for driving the sheet collecting and transfer carrier grippers at the surface speed of the web and the sheet delivery carrier grippers at a lesser surface speed.
